FOUNDATION FOR ELASTIC FLUID TURBINES AND THE LIKE

James L. Roberts, Schenectady, N. Y., assignor to
General Electric Company, a corporation of
New York

Application December 11, 1943, Serial No. 513,984

4 Claims. (Cl. 253—1)

The present invention relates to foundations for elastic fluid turbines and like machines subject to high temperatures during operation. More specifically, the invention relates to foundations including a concrete block or blocks and a sole plate or plates attached thereto for supporting a turbine or other machine on the block. Difficulties have heretofore been experienced with such arrangements due to growing and uneven expansion of the concrete caused by heat transmission from turbines supported thereon. Great temperature changes of the block, especially nonuniform heating may cause misalignment of the turbine and require frequent aligning thereof. In certain instances it has been found that temperature differences in the block may be of such magnitude as to cause bending and warping of heavy sole plates.

The object of my invention is to provide an improved construction of foundations including concrete blocks whereby the aforementioned drawback is considerably reduced.

For a consideration of what I believe to be novel and my invention, attention is directed to the following description and the claims appended thereto in connection with the accompanying drawing.

Fig. 1 illustrates a turbine foundation arrangement embodying my invention; Fig. 2 is an enlarged view along line 2—2 of Fig. 1; and Fig. 3 is an enlarged sectional view along line 3—3 of Fig. 2.

The arrangement comprises an elastic fluid turbine 10 with an exhaust end 11 and a bearing 12 for supporting a turbine shaft near the exhaust end 11. The foundation for the bearing 12 comprises a concrete block 13 and a sole plate 14 on the upper face of the block with grooves 15 keyed to the bearing casing by means of keys 16. Heat may be transmitted from the turbine to the concrete foundation block 13 by conduction through the sole plate 14 and also by radiation from the turbine towards the side of the block facing the turbine.

Means are provided to reduce the transmission of heat from the turbine to the foundation block and to assure uniform heating of the latter. In the present example this means comprises a plurality of series-connected tubes 17 having an inlet 18 and an outlet 19 and being located adjacent the lower side of the sole plate 14 and securely fastened thereto by means of a plurality of spaced welds 20. The triangular spaces between each tube 17 and the sole plate 14 are filled in by a pliable cement or putty 21 of good

heat conductivity in order to assure good heat flow from the sole plate 14 to the cooling tubes 17. The spaces between adjacent tubes are filled in by concrete of the block 13.

5 The side of the block 13 facing the turbine exhaust end is covered with a layer of asbestos 22 or like material of low heat conductivity. The asbestos in turn is lined with series-connected cooling tubes 23 similar to the tube 17 10 for the sole plate. During operation, water or like cooling medium is conducted through the tubes 17 and 23, thus carrying away a considerable amount of heat conducted through the sole plate to the tube 17 and radiated towards the tubes 23. As far as heat is actually transmitted from the turbine to the concrete block 13, such heat is uniformly distributed within the block by action of the cooling tubes and the insulating cover, thus reducing to a minimum uneven expansion of the block and the sole plate. The 15 temperature of the concrete foundation block may be controlled by controlling the amount of water or like cooling medium conducted through the cooling tubes. With this arrangement the 20 turbine is kept in alignment and expense in correcting the alignment at frequent intervals is 25 materially reduced.

Having described the method of operation of my invention, together with the apparatus which 30 I now consider to represent the best embodiment thereof, I desire to have it understood that the apparatus shown is only illustrative and that the invention may be carried out by other means.

What I claim as new and desire to secure by 35 Letters Patent of the United States, is:

1. Foundation for elastic fluid turbines and like machines subject to high temperature comprising a block, a sole plate on the block, and cooling means between the sole plate and the 40 block to reduce heat transfer through the sole plate to the block.

2. Foundation for elastic fluid turbines and like machines subject to high temperature comprising a block of concrete, a sole plate supported on the block and cooling means between the sole plate and the block to reduce heat transfer through the sole plate to the block, said cooling means comprising series-connected tubes 45 arranged in the supporting surface of the block and a cement of good heat conductivity filling the spaces between the respective tubes and the sole plate to assure good heat transmission from the plate to the tubes.

3. Foundation for elastic fluid turbines and like machines subject to high temperatures dur-

ing operation comprising a concrete block, a sole plate on the block, means for cooling the sole plate to reduce heat transfer to the concrete block and other means for reducing heat radiation towards a side of the block, said other means comprising a sheet of material of low heat conductivity attached to said side.

4. Foundation for elastic fluid turbines and like machines subject to high temperatures dur-

ing operation comprising a concrete block, a sole plate on the block, means for cooling the sole plate to reduce heat transfer to the concrete block, and other means for reducing heat radiation towards a side of the block, said other means comprising a sheet of material of low heat conductivity attached to said side and cooling tubes attached to said sheet.

JAMES L. ROBERTS.
